UNITED STATES PATENT OFFICE.

JAMES F. CALDWELL, OF WATTS, CALIFORNIA.

AQUATIC VEHICLE.

Application filed October 31, 1927. Serial No. 230,912.

My invention relates to and has for a purpose the provision of a vehicle capable of floating in the water and supporting a person in either a seated posture or a swimming position wherein the lower part of the body of the person is submerged, the vehicle embodying simple and substantial means by which the person can propel the vehicle through the water while in either position, to the end that one can enjoy the water without the necessity of physical exertion to remain afloat and can move about in the water with a minimum amount of effort.

It is a further purpose of my invention to provide an aquatic vehicle of the above described character which is comparatively light in weight and is capable of being folded into a relatively small and compact parcel for transportation or storage, yet can be quickly set up for use to form a rigid and stable structure in the water so that one without a knowledge of swimming can safely float upon the water on the vehicle or propel the latter through the water at will.

I will describe only one form of aquatic vehicle embodying my invention and will then point out the novel features in claims.

In the accompanying drawing,

Fig. 1 is a view showing in vertical longitudinal section one form of aquatic vehicle embodying my invention, and illustrating the vehicle set up for use;

Fig. 2 is a view similar to Fig. 1 and illustrating the folded position of the vehicle;

Fig. 3 is a plan view of the vehicle;

Fig. 4 is a detail sectional view taken on the line 4—4 of Fig. 6 and looking in the direction of the arrows;

Fig. 5 is a sectional view taken on the line 5—5 of Fig. 1 and looking in the direction of the arrows; and

Fig. 6 is an enlarged sectional view illustrating a connector and latching means therefor embodied in my invention.

Referring specifically to the drawing in which similar reference characters designate similar parts in each of the several views, my invention in its present embodiment comprises a buoyant means in the form of a pair of floats F and F' preferably constructed of metal, each of the floats consisting of forward and rear watertight sections 10 and 11 respectively, of hollow cylindrical form, the forward sections being tapered at their front ends as indicated at 12 so as to reduce to a minimum the resistance offered by the

floats to forward movement in the water, and being provided with metal bands or straps 13 to which is secured, in the inclined position shown in Fig. 1, and by fastening members 14, a support designated generally at S preferably of wood in the form of a flat board on which an operator is adapted to rest in a manner to be hereinafter described. The support S serves also to rigidly connect the forward sections so as to definitely position the pair of floats in side by side spaced relation, and the forward and rear sections of each float are connected to each other at their undersides by means of a hings 15 so that the sections can occupy the extended position shown in Fig. 1 wherein they are disposed in end to end relation, or a folded position as shown in Fig. 2 wherein the sections are disposed alongside each other. The sections of each float are secured in extended position by means of a hasp 16, hinged at 17 to the forward section and receiving an eye 18 secured to the rear section, after which a pin 19 is extended through the eye to thus prevent displacement of the hasp.

To provide means for supporting a propelling means P and an actuating means A for the propelling means, in a submerged position and at a predetermined depth when the vehicle is placed in the water, a frame designated generally at K depends from the floats F and F'.

The frame in the present instance comprises a member constituting a housing 20 for the actuating means A, a pair of members 21 having their upper ends pivotally connected at 22 to bands or straps 23 secured to the rear sections 11 and their lower ends pivotally connected at 24 to ears 25 formed on the tubular portion 26 of the housing 20, and a connector 27 detachably connected at its ends to the circular portion 28 of the housing and to the support S.

The connector 27 comprises a metal bar of angular cross section provided at its ends with sleeves constituting sockets 29 and 30, which freely receive heads 31 and 32 respectively secured to the portion 28 of the housing and to the underside of the support S. The head 31 is provided with a radially projecting pin 33 which is received in an L-shaped slot 34 formed in the socket 29 so as to prevent endwise displacement of the connector, while the head 32 is provided with a pin 35 extending transversely through the head and projecting from opposite sides

thereof for engagement within diametrically opposed slots 36 formed in the socket 30. The connector is adapted to be latched to the head 32 by means of a latching arm 37 having a slot 38 receiving the L-shaped head 39 of the pin 35, the arm being pivoted at 40 on an actuating lever 41, pivoted at 42 on the connector. The free end of the lever 41 is provided with a leaf spring 42 bent to provide a projection 43, while a keeper 44 slideable on the connector is adapted to be pushed over the leaf spring to a point above the projection 43 so as to latch the actuating lever against movement and thus maintain the latching arm 37 in latching engagement with the pin 35.

In applying the connector to the heads 31 and 32 and assuming that the latching arm 37 and actuating lever 41 occupy the position shown in dotted lines in Fig. 6, the socket 29 is first extended over the head 31 until the pin 33 is received in the inner end of the longitudinal portion of the slot 34 after which the connector is rotated until the pin 35 is positioned at the inner end of the circumferential portion of the slot, at which time the slots 36 of the socket 30 will be positioned to receive the projecting ends of the pin 35 upon extending the socket 30 over the head 32. With the pin 35 seated at the inner end of the slots 36 the latching arm 37 and actuating lever 41 are manipulated until the head 39 of the pin 35 is received in the slot 38, after which the lever 41 is rocked to the position shown in full lines in Fig. 6, thus drawing the arm 37 downwardly beneath the head 39 of the pin 35 to prevent disengagement of the arm from the pin. The keeper 44 is then pushed over the spring 42 to complete the connecting operation, thus positively preventing displacement of the sockets 30 and 32 from their respective heads.

The actuating means in the present instance comprises a drive shaft 45 journaled centrally in the circular portion 28 of the housing 20 and in a cover plate 46 closing the open side of the housing, the shaft projecting from the side of the housing and cover plate and having secured thereto a pair of arms 47 in opposed relation, provided with pedals 48. A bevel gear 49 is fixed to the shaft 45 and meshes with a pinion 50 fixed to the forward end of a driven shaft 51 journaled in the tubular portion 26 of the housing, while to the projecting rear end of the shaft 51 is secured a screw propeller 52 constituting the propelling means P. Secured to the rear end of the tubular portion 26 is a spider 53 carrying a wire mesh guard 54 which encloses the propeller 52 so as to prevent any one from coming in contact with the propeller and possibly being injured by the latter when in motion.

In the operation of the vehicle, it is pushed out in the water by the operator who then

climbs aboard the vehicle and positions himself between the floats F and F' with his feet resting on the pedals 48 and his stomach and chest resting upon the support S so as to occupy substantially a swimming position. 70 The arms of the operator can be extended to rest upon the forward sections 10 of the floats, and upon actuation of the pedals 48 the propeller 52 will be rotated to propel the vehicle through the water. Should the operator desire to assume a seating posture a seat is provided which comprises a web of canvas 55 secured at one end to a strap 56 embracing one of the rear float sections 11 and provided with hooks 57 adapted to be hooked into openings formed in a bar 58 secured to the other rear float section by means of a strap 59 embracing the section. With the operator seated on the web 55 the pedals 48 can be actuated as before and the vehicle propelled 80 through the water. 85

By the provision of the pivotal connections 22 and 24 and the detachable connector 27, the frame K is rendered foldable, so that upon detaching of the connector the housing 20 can be swung upwardly on the pivotal connection 24 to a position between the pair of members 21 and the members and housing then swung upwardly upon the pivotal connection 22 until disposed between the rear float sections 11. 90 Upon removing the pins 19 from the eyes 18 and then swinging the hasps 16 upwardly, the forward float sections 10 can be swung downwardly on the hinge 15 to their folded position, all of which is clearly shown in Fig. 2, 100 to the end that the vehicle will form a relatively small and compact parcel for transportation or storage, yet can be quickly set up to form a rigid and stable structure. 105

It will be noted that the housing is provided with openings 60 through which water can enter the housing and thus serve as a lubricating medium for the moving parts in the housing.

Although I have herein shown and described only one form of aquatic vehicle embodying my invention, it is to be understood that various changes and modifications may be made therein without departing from the spirit of the invention and the spirit and scope of the appended claims. 110

I claim as my invention:

1. An aquatic vehicle comprising a pair of floats, means for rigidly connecting the floats in side by side spaced relation and constituting a support on which an operator is adapted to rest, a foldable frame depending from and connected to the floats, propelling means carried by the frame, and means carried by the frame for actuating the propelling means and adapted for operation by the feet of the operator when resting on said support. 120

2. An aquatic vehicle comprising a pair of floats, each of which includes a forward section and a rear section hingedly connected to 130

occupy an extended position wherein the sections are disposed in end to end relation, or a folded position wherein the sections are disposed alongside each other, a support secured 5 to the forward sections for rigidly connecting the floats in side by side spaced relation, propelling means for the vehicle, means for actuating the propelling means, a frame comprising a member for supporting said propelling and actuating means, a pair of members pivotally connected at one of their ends to the rear sections and at the other of their ends to the first member, a connector, and means for detachably connecting said connector to the first member and to said support, whereby when said connector is detached, the first member and pair of members can be swung upon their pivotal connections to a position substantially in the plane of the 15 sections and will co-operate with the sections when in folded position to form a relatively compact parcel.

3. An aquatic vehicle as embodied in claim 2 wherein said first member comprises a housing, and said actuating means comprises a drive shaft journaled in the housing, arms on the shaft exteriorly of the housing, pedals on the arms, a driven shaft journaled in the housing at an angle to the first shaft, and gears 20 in the housing fixed to the shafts and disposed in meshing relation, said propelling means comprising a propeller secured to the driven shaft.

4. An aquatic vehicle as embodied in claim 2 wherein said detachable connecting means comprises heads secured to the first member and support, sockets at the ends of said connector receiving said heads, and means for latching the sockets to the heads.

5. An aquatic vehicle as embodied in claim 2 wherein said detachable connecting means comprises heads secured to the first member and support, sockets at the ends of said connector receiving said heads, and means for latching the sockets to the heads comprising pins projecting from the heads, an L shaped slot in one of said sockets receiving the pin of the respective head, slots in the other socket receiving the pin of the other head, a latching arm having an opening adapted to receive the projecting end of the pin of the other head, an actuating lever pivoted on the connector and to which the latching arm is pivotally connected, for moving the arm into latching engagement with the pin, and co-acting means 55 on the lever and connector for maintaining the arm in latching engagement with the pin.

6. An aquatic vehicle as embodied in claim 2 wherein said detachable connecting means comprises heads secured to the first member and support, sockets at the ends of said connector receiving said heads, and means for latching the sockets to the heads comprising pins projecting from the heads, an L shaped slot in one of said sockets receiving the pin of

the respective head, slots in the other socket receiving the pin of the other head, a latching arm having an opening adapted to receive the projecting end of the pin of the other head, an actuating lever pivoted on the connector and to which the latching arm is pivotally connected, for moving the arm into latching engagement with the pin, and co-acting means comprising a spring on the lever and a keeper 70 slideable on the connector into latching engagement with the spring, for maintaining the arm in latching engagement with the pin. 75

7. An aquatic vehicle comprising a pair of floats, means for rigidly connecting the floats in side by side spaced relation and constituting a support on which an operator is adapted to rest, propelling means for the vehicle, manually operable means for actuating the propelling means, and a foldable frame depending from and connected to the floats, for supporting the propelling and actuating means in a submerged position in a body of water.

8. An aquatic vehicle comprising a pair of floats, each of which includes a forward section and a rear section hingedly connected to occupy an extended position wherein the sections are disposed in end to end relation, or a folded position wherein the sections are disposed alongside each other, means for securing the sections in extended position, a support secured to the forward sections for rigidly connecting the floats in side by side spaced relation, propelling means for the vehicle, manually operable means for actuating the propelling means and a foldable frame depending from the floats and including a member for supporting the propelling and actuating means and other members movably connected to the first member and 100 to the rear sections of the floats, and a connector detachably associated with the first member and the forward sections of the floats. 105

9. An aquatic vehicle comprising a pair of floats, means for rigidly connecting the floats in side by side spaced relation and constituting a support on which an operator is adapted to rest, a frame depending from and connected to the floats, propelling means carried by the frame, and means carried by the frame for actuating the propelling means and adapted for operation by the feet of the operator when resting on said support, said frame comprising a member for supporting said propelling and actuating means, a pair of members movably connected to the floats and said first member, a connector, and means for detachably connecting said connector to said first member and support. 115 120 125

10. An aquatic vehicle comprising buoyant means, propelling means for the vehicle, means for actuating the propelling means, and a frame for supporting the propelling and actuating means, said frame comprising 130

a plurality of members movably connected to the buoyant means, a single member movably connected to the plurality of members, a connector, and means for detachably connecting said connector to the single member and buoyant means.

11. An aquatic vehicle comprising buoyant means including a support on which an operator is adapted to rest, propelling means for the vehicle, means for actuating the propelling means, and a frame comprising a member for supporting the propelling and actuating means, means for movably connecting the member at one point to the buoyant means, and detachable means for rigidly connecting the member at another point to the buoyant means.

12. An aquatic vehicle comprising a plurality of floats, each of which includes forward and rear sections movably connected to occupy an extended position, or a folded position, means for maintaining the sections in extended position, means for connecting the floats in spaced relation, propelling means for the vehicle, means for actuating the propelling means, and a foldable frame comprising a member for supporting the propelling and actuating means, means for movably connecting the member at one point to the floats, and detachable means for rigidly connecting the member at another point to the floats.

13. An aquatic vehicle as embodied in claim 12 wherein said means for connecting

the floats comprises a support inclined downwardly and rearwardly and rigidly connecting the forward sections in side by side spaced relation.

14. An aquatic vehicle comprising a pair of floats, means for rigidly connecting the floats in side by side parallel relation with sufficient space between the floats to freely receive the body of an operator therebetween, a frame depending from and connected to the floats, propelling means carried by the frame, and foot actuated means carried by the frame for actuating the propelling means, and including treadles engageable by the feet of the operator, the first means constituting a support presenting a flat surface inclined downwardly and rearwardly of the vehicle, on which the chest and abdominal portions of an operator's body when positioned between the floats, are adapted to rest, the rear end of the support being so positioned at a point above the foot treadles, that with the chest and abdominal portions of the operator's body resting upon the support, the lower portion of the body from the hips downward will be free to bend and assume substantially a standing position with the feet of the operator in engagement with the foot treadles so that the weight of the operator will be partially supported on the treadles and can be applied directly downward on the treadles to most effectively operate the latter.

JAMES F. CALDWELL.
